Inventor: James Waters

United States Patent Office.

JAMES S. WATERS, OF ST. LOUIS, MISSOURI, ASSIGNOR TO THE ST. LOUIS LEAD AND OIL COMPANY, OF THE SAME PLACE.

Design No. 2,707, dated July 16, 1867.

DESIGN FOR A TRADE-MARK.

The Schedule referred to in these Letters Patent and making part of the same.

TO ALL WHOM IT MAY CONCERN:

Be it known that I, JAMES S. WATERS, of the city and county of St. Louis, in the State of Missouri, have originated and designed a new Design for a Trade-Mark, of which the following is a full, clear, and exact description, reference being had to the annexed drawing, making part of this specification.

My design consists of a spur-gear, combined and united with the astronomical sign of the planet Saturn, substantially in the manner shown in the drawing annexed.

This is intended to be affixed either as a brand, or in the shape of an engraving, to articles of manufacture, and when used as a brand, the spur-gear, as well as the astronomical sign, will have such breaks in them as may be necessary to give the requisite strength to the stencil or other plate by which the impression may be made.

What I claim as my invention, and desire to secure by Letters Patent, is—

The design for a trade-mark as set forth and shown.

JAS. S. WATERS.
